(57) **CLAIM**

The ornamental design for a sensor array, as shown and described.

DESCRIPTION

This invention was made with U.S. Government support under Agreement Number 75A50122C00028, awarded by the U.S. Department of Health and Human Services. The U.S. Government has certain rights in the invention.

FIG. 1 is a perspective view of a sensor array;

FIG. 2 is a top view of the sensor array shown in FIG. 1;

FIG. 3 is a bottom view of the sensor array shown in FIG. 1;

FIG. 4 is a left side view of the sensor array shown in FIG. 1;

FIG. 5 is a right side view of the sensor array shown in FIG. 1; and,

FIG. 6 is a front view of the sensor array shown in FIG. 1. The broken lines in the figures depict portions of the sensor array that form no part of the claimed design.

1 Claim, 6 Drawing Sheets
